UNITED STATES PATENT OFFICE.

GEORGE P. MITCHELL, OF GALVA, ILLINOIS.

WINDOW-BLIND.

No. 881,433.

Specification of Letters Patent. Patented March 10, 1908.

Application filed September 11, 1907. Serial No. 392,349.

To all whom it may concern:

Be it known that I, GEORGE P. MITCHELL, a citizen of the United States, residing at Galva, in the county of Henry and State of Illinois, have invented a new and useful Window-Blind, of which the following is a specification.

This invention relates to window blinds.

The object of the invention is to provide a blind that shall be capable of ready adjustment to window frames of different widths, and adapted for disposal either above the upper or below the lower sash, and that will allow free passage of air to a room but will 10 positively preclude entrance of rain, whereby with houses that are not equipped with shutters it will not be necessary to close the windows during a rain storm, thereby obviating a source of much discomfort to the 15 occupants, especially if the storm be one of long duration. Furthermore, to render it possible for a house holder to air the house during her absence without being subjected to worry from fear that rain will beat in the 20 windows.

With the above and other objects in view, as will appear as the nature of the invention is better understood, the same consists, generally stated, in a window shutter comprising 25 two sections each embodying angularly-disposed slats of the same general construction as those of an ordinary shutter, the slats being adapted to overlap and have sliding movements relatively to each other, whereby 30 to adapt the structure to window frames of different widths.

The invention consists further in the various novel details of construction of a window blind, as will be hereinafter fully described 35 and claimed.

In the accompanying drawings forming a part of this specification and in which like characters of reference indicate corresponding parts,—Figure 1 is a view in front elevation, partly broken away, of a window blind constructed in accordance with the present invention. Fig. 2 is a vertical longitudinal sectional view on the line 2—2, Fig. 1, and looking in the direction of the arrow thereon. 45 Fig. 3 is a fragmentary detail view of a portion of the structure shown in Fig. 1.

The blind comprises two sections designated, generally, 1 and 2. One of the sections, in this instance, the section 2, is composed of a stile 3 and a guide 4, each of which 50 is provided with obliquely-disposed slots or

seats 5 and 6, the latter being shown in Fig. 3, to receive the slats 7. As shown in Figs. 2 and 3, the seats 6 do not extend entirely across the stile and guide 4 but terminate 60 short of one edge thereof, and the slats 7 project beyond the forward edge of the parts in order to be more effective in shedding rain, and also to simplify the construction of the article, as it will be easier to cut the seats as 65 shown, which may be done by a saw, than it would be to mortise them in the ordinary manner.

The slats 7 are secured in the stile 3 in any preferred manner as by nails 10 or if preferred a suitable adhesive may be employed, or both an adhesive and nails.

The guide 4 has combined with it a keeper 11 that is formed of a strip of metal preferably galvanized iron secured at its upper end 12 to 75 the guide, thence deflected laterally, as at 13, to afford space for the slats to move, the lower end of the keeper being bent and secured to the lower end of the guide at 14.

The section 1 embodies a stile 15 of the 80 same construction as the stile 3 and in which are rigidly secured the slats 16 in the same manner as that above described. These slats are adapted to overlie the slats 7 of the section 2 and to work in the slots 5 of the 85 guide, as clearly shown in Fig. 2, the keeper 11 serving to prevent the slats from having any rocking motion relatively to each other and also to maintain them in alinement, and in a great measure to relieve the holding 90 means 10 from undue strain.

From the arrangement described it will be seen that the two sections 1 and 2 may be readily adjusted so as to fit any size of window frame, such adjustment being indicated 95 by dotted lines in Fig. 1, and further that the blind may be placed under the lower sash or above the upper sash, as may be preferred, and thereby positively secure the objects sought. In order to stay the stile 3 and 100 guide 4 against relative movement or any tendency to yield when the sections are moved inward and outward in order to accommodate them to the window frame, a brace 17 is employed which is by preference 105 made of a strip of galvanized iron and is firmly secured to the back of the stile and to the guide, as shown in Figs. 1 and 2.

It will be seen from the foregoing description that there is a common and underlying 110 feature present in each of the forms shown, namely, that of permitting adjustment of the

shutter to compensate for different widths of one frame.

What is claimed is:—

A blind comprising two sections adapted for sliding movements relatively to each other, each section comprising an end stile having obliquely disposed seats open at one end and one of the sections having a guide provided with obliquely disposed similarly 10 constructed seats, slats secured in the seats of the stiles and overlapping and projecting

through the seats of the guide, means for holding the slats in the latter seats, and a brace connecting one of the stiles and the guide.

In testimony that I claim the foregoing as my own, I have hereto affixed my signature in the presence of two witnesses.

GEORGE P. MITCHELL.
